CLAIM

The ornamental design for an angled chisel brush, as shown and described.

DESCRIPTION

FIG. 1 is a top, front, left side perspective view of my new design of an angled chisel brush.

FIG. 2 is a front, top side perspective view thereof.

FIG. 3 is a left side elevational view thereof; the right side elevational view being a mirror image thereof.

FIG. 4 is a front side elevational view thereof.

FIG. 5 is a back side elevational view thereof.

FIG. 6 is a top plan view thereof; and,

FIG. 7 is a bottom plan view thereof.

The broken lines showing the ferrule and handle in FIGS. 1, 2, 3, 4, 5, and 7 are included to show environmental structure and form no part of the claimed design.

1 Claim, 2 Drawing Sheets# US D900,480 S
